UNITED STATES PATENT OFFICE

DANIEL I. REITER, OF NEW YORK, N. Y.

PRONGED FASTENER

Application filed April 12, 1929. Serial No. 354,499.

This invention relates to the socket elements of snap fasteners and particularly, to that type of sockets as can be made of a single piece of material.

5 My improved socket is particularly designed to be used in connection with carpet fasteners, in which a series of prongs are usually provided for fastening the socket to another article, such as a piece of fabric or 10 carpet.

The various objects of my invention will be clear from the description which follows and from the drawings, in which,

15 Fig. 1 is a top plan view of one form of my improved one-piece socket.

Fig. 2 is a vertical section of the same, taken on the line 2—2 of Fig. 1.

Fig. 3 is a view similar to Fig. 1, of a socket wherein the fingers are made of some 20 what different form.

Fig. 4 is a vertical section of the same, taken on the line 4—4 of Fig. 3.

Fig. 5 is a view, similar to Figs. 1 and 3, showing a modified arrangement and form 25 of the resilient fingers, and

Fig. 6 is a vertical section of the same, taken on the line 6—6 of Fig. 5.

In that practical embodiment of my invention which I have illustrated by way of example, a one-piece socket is provided with an apertured bottom wall 10, having a preferably centrally arranged aperture 11 therein. A stud of any of the well known types is intended to be passed through the aperture 11 30 for engagement with the yieldable or resilient fingers soon to be described.

Integral with the bottom wall 10 and preferably arranged at substantially right angles thereto at its outer edge, is the preferably 40 cylindrical outer wall 12. Said wall serves to space the exposed face 14 of the bottom wall 10 below the surface of the article to which the socket is attached, and thereby provides sufficient room in the socket for the 45 insertion and retention of a comparatively shallow cooperating stud of the type well known in the art.

For attaching the socket to another article, such as for instance, a piece of carpet or 50 other similar material, I prefer to use the

pointed prongs 13, which are spaced apart about the peripheral edge of the wall 12 and which are substantially continuous and integral therewith. The prongs 13 are intended to be passed through the article to which the socket is to be attached and to be bent down or turned over in either direction on the face opposite to that against which the socket rests, as is well understood.

For receiving and resisting the withdrawal 60 of the head of a stud passed through the aperture 11, I provide a series of yieldable or resilient fingers, in spaced relation to each other and continuous and integral with the wall 12, and preferably projecting from the 65 upper end of said wall.

It will be understood that the resilient fingers, no matter of what shape the ends thereof are made, should be of sufficient length to inwardly overhang the peripheral 70 edge of the aperture 11 so as to engage a stud passed through said aperture.

As illustrated in Figs. 1 and 2, the resilient fingers 15 are arranged between adjacent pairs of prongs 13 and have substantially 75 parallel sides 16, and an end 17 substantially perpendicular to said sides. Said fingers 15 as is illustrated, are bent into the shape of an

S. Each finger is shown as being bent downwardly and inwardly from the wall 12, the 80 end 17 thereof being reversed, or bent upwardly and outwardly, so as to provide a cylindrical surface on the end 17 projecting inwardly past the edge of the aperture 11 to a slight extent, and offering a slight resistance to the passage of the stud. The curvature of the end 17, however, and the size of said end conforms to the shape of the constricted portion of a stud with which my improved socket is intended to cooperate.

As illustrated in Figs. 3 and 4, the resilient fingers 20 are arranged similarly to the fingers 15 between adjacent pairs of prongs 13, and are first bent downwardly and inwardly 90 from the wall 12 and then slightly upwardly.

This results in bringing the ends 21 slightly inwardly of the peripheral edge of the aperture 11, so that said fingers are protected from injury by the bottom wall 10.

In that form of the resilient fingers illus-

trated in Figs. 5 and 6, the fingers 22 may be arranged between alternate pairs of prongs so as to provide a set of four fingers instead of the set of eight shown in Figs. 1 to 4 inclusive. The resilient fingers 22 are further illustrated as modified to the extent that the ends 23 are bent downwardly and outwardly so as to provide a closed, substantially cylindrical surface 24 for engaging the stud.

10 The remaining projections 25 while integral with the wall 12 and arranged between the other alternate pairs of prongs, are of insufficient length to act as stud engaging members, but serve not only to brace the socket but also may serve to engage the surface to which the socket is attached and thereby serve as stops to prevent the fastener from cutting its way through the carpet, the fingers 15, 20 and 22 also serving to prevent such cutting.

15 It will be understood that in all the various possible shapes of the resilient fingers, said fingers are integral with the wall 12 and bent inwardly and downwardly or laterally therefrom, and are of sufficient length to allow the substantially free inner ends thereof to inwardly overhang the edge of the aperture 11 for the purpose of engaging the stud passed through said aperture.

20 It will also be understood that the ends of the resilient fingers are suitably curved to resist the withdrawal of the stud from the socket after it once has been inserted thereinto, since the ends of said fingers are designed to engage the constricted portion of any of the well known types of studs which are customarily used in connection with shallow sockets, and hence which need not be shown. It will be further understood that the various fingers 15, 20 and 22 are designed to yield on the advance of the stud through the aperture 11 under the action of the stud on the free ends of the fingers, so as to allow the passage of said stud through the aperture and past the ends of the resilient fingers without the necessity of applying undue pressure to the stud.

25 Said resilient fingers also yield in substantially the same manner when the stud is forcibly withdrawn from the socket.

30 It will be seen that I have provided a simple socket adapted to be readily attached to another article and made of one piece of material, wherein resilient fingers for engaging and temporarily retaining a stud are provided, and wherein said fingers are protected from injury by a bottom wall.

35 It will also be understood that while I have shown and described various forms of my invention as illustrative thereof, I do not intend to limit myself thereto, but intend to claim my invention as broadly as may be permitted by the state of the prior art and 40 the terms of the appended claims.

1 claim:

1. A pronged socket comprising an outer wall, spaced prongs integral with and outstanding from the upper end of said wall, a bottom wall portion having an aperture therein for the reception of a stud, bent from the lower edge of said outer wall and substantially perpendicular thereto, and yieldable fingers integral with the upper end of the outer wall and bent inwardly therefrom and extending from said upper end to a point inwardly of the edge of the aperture for engaging said stud.

15 2. A stud-engaging fastener element of a single piece of material, including an outer wall and an apertured bottom wall, spaced prongs outstanding from and integral with the upper end of said outer wall, and yieldable fingers integral with said outer wall and bent from the upper end thereof, the inner ends of said fingers being free and curved, and projecting slightly inwardly of the aperture of said bottom wall and being adapted to engage the constricted portion of a cooperating stud passed through said aperture.

20 3. In a socket fastener element, a bottom wall having an aperture therein, a substantially cylindrical outer wall, a pair of prongs continuous with said outer wall and spaced apart and extending beyond a peripheral end of said outer wall, and a finger integral with said outer wall and bent radially inwardly from the same peripheral end between said prongs to overhang the aperture of said bottom wall and to engage a stud passed through the aperture.

25 4. In a stud-engaging socket fastener, an apertured bottom wall adapted to have a stud element passed therethrough, spaced prongs integral with and outstanding substantially perpendicularly to means formed on the outer periphery of said wall, and resilient members bent radially inwardly of said apertured wall and from said means on the outer periphery, and arranged between said prongs with their free ends curved and terminating adjacent the edge of said aperture for engaging a constricted portion of a stud passed through the aperture.

30 5. In a stud-engaging socket fastener element, a flat circular apertured bottom wall, a substantially cylindrical wall integral with and substantially perpendicular to said bottom wall, spaced members on the upper end of the cylindrical wall for attaching said element to an article, and yieldable elements bent inwardly from and integral with said end of said cylindrical wall and projecting inwardly past the edge of the aperture in said bottom wall for engaging the head of a stud passed through said aperture.

35 6. In a stud-engaging socket, an outer wall, spaced yieldable fingers bent inwardly from the upper end of said outer wall and integral therewith, apertured means bent from the

other end of said outer wall and adapted to have a cooperating stud passed through the aperture thereof and into engagement with said fingers, and attaching means for the socket projecting from the upper end of said wall.

7. In a one-piece stud-engaging fastener socket, adapted to be attached to a carpet with its uppermost end adjacent the back of the carpet, an annular outermost portion, spaced resilient elements bent inwardly from the upper end of said portion and downwardly, an apertured member bent from the other end of said portion, the edge of the aperture of said member being arranged outwardly of the ends of said elements whereby a stud passed through said aperture engages said elements and projecting members adapted to be passed into the carpet and bent, extending upwardly from said upper end and alternating with said elements.

8. In a one-piece stud-engaging carpet fastener socket, an apertured bottom wall, an outer wall, a plurality of prongs integral with the outer wall and continuous therewith and a plurality of yieldable fingers formed from the material between the prongs bent inwardly and downwardly from said outer wall toward the aperture of said bottom wall and integral with said outer wall, and of sufficient length to inwardly overhang the edge of said aperture and to engage a stud passed through the aperture.

35 9. In a one-piece stud-engaging socket having a stud-receiving aperture at the lower end thereof, an outer wall, means integral with and extending from one end of said wall for securing the element to another article, and means bent from and integral with the aforementioned end of said wall for engaging and for resisting the withdrawal of a stud from said socket after the stud has been passed through the aperture.

45 10. In a one-piece socket provided with a stud-receiving aperture, an outer wall adapted to be secured in place with its upper edge adjacent the back of a carpet, spaced yieldable fingers bent inwardly and downwardly from the upper end of said wall, the inner portions of said fingers being adapted to engage, and yield radially under the influence of, a stud inserted into and withdrawn from the aperture of said socket, and fastening members extending upwardly from said upper end at points between the fingers.

55 11. In a one-piece socket, an outer wall, inwardly bent resilient fingers integral at their outer extremities with one end of said wall and substantially free at their inner extremities, said inner extremities being curved, an apertured member bent from the other end of said wall for protecting and partly covering said fingers, and bendable pointed prongs ex-

tending from said first mentioned end of the wall.

12. In a one-piece stud-engaging socket, an outermost wall, spaced resilient elements bent from the upper end of said wall and integral therewith, means integral with and extending from said end of said wall for securing the socket to another article, and apertured means extending from the lower end of said wall for protecting said elements, said elements being of sufficient length to surround the aperture in said apertured means and to engage the head of a stud inserted through said aperture.

13. In a one-piece socket, a bottom wall provided with a stud-receiving aperture, an outer wall, spaced prongs upstanding from the upper end of the outer wall, spaced projections extending from the upper end of the outer wall and arranged substantially parallel to and above the bottom wall and terminating outwardly of the aperture, and resilient stud-engaging means between the projections and extending from the upper end of the outer wall inwardly into operative stud-engaging relation to the aperture.
